UNITED STATES PATENT OFFICE.

CLARENCE S. CRANE, OF CHAMPAIGN, ILLINOIS, ASSIGNOR OF ONE-HALF TO EUGENE I. BURKE, OF CHAMPAIGN, ILLINOIS.

BENDING MACHINE.

Application filed December 27, 1923. Serial No. 632,901.

To all whom it may concern:

Be it known that I, CLARENCE S. CRANE, a citizen of the United States, residing at Champaign, in the county of Champaign and State of Illinois, have invented certain new and useful Improvements in Bending Machines, of which the following is a full, clear, and exact description.

This invention relates to bending machines, and particularly to those for imparting one or more bends to a strip of material. Such a machine has great utility in the bending of strips of reinforcing material into the proper form or shape for the reinforcement of concrete stairs. An object of the invention is to provide an improved machine for this purpose, which will perform the desired bending operations on strips of material in a rapid and satisfactory manner, and which is simple, durable, and relatively inexpensive. Other objects and advantages will be apparent from the following description of an embodiment of the invention, and the novel features will be particularly pointed out hereinafter in claims.

In the accompanying drawing:

Figure 1 is an elevation partly in section of a machine constructed in accordance with the invention;

Fig. 2 is a similar view, with the parts in a different relative operative position; and

Fig. 3 is a sectional elevation of a portion of the machine on a slightly larger scale, the parts being in the relative positions shown in Fig. 2.

In the illustrated embodiment of the invention, a suitable frame composed of vertical posts 1 and horizontal connecting bars 2 is mounted upon skids or runners 3, by means of which the machine may be drawn from one job to another. A sill 4 is disposed crosswise of the interior of the frame adjacent one end, and is mounted in the frame for rotation about a horizontal axis 4^a. The sides of the frames are each provided with parallel spaced posts 5 at the ends of the sill 4, and a clamping gate member 6 extends across the interior of the frame and is slidably disposed between the pairs of posts 5 at opposite sides of the frame. The clamping gate member is capable of vertical sliding movement between the posts 5 so as to be movable into and out of clamping engagement with the sill 4 at one side of a

vertical plane through the axis of rotation 5^a of the sill. The gate member is composed of upper and lower sections, the lower section 6^a being hinged at 7 to the lower edge of the upper section so as to be capable of swinging upwardly and away from the sill 6^a

4. The upper section of the clamping gate is secured in any suitable manner, such as by bolts 8 to intermediate portions of clamping levers 9 which extend lengthwise of the frame, the levers being pivoted at 10 to the forward posts 1 of the frame.

A pair of rocker arms 11 are hinged upon a rod 12 extending between the opposite sides of the frame, the rod 12 being mounted adjacent to but slightly below an overhanging portion of the sill 4. A plate 13 is secured to each rocker arm 11 by means of bolts 14, which pass through apertures in the plates 13 and through slots 15 in the rocker arms. The slots are elongated lengthwise of the rocker arms so that when the bolts 14 are loosened, the plates 13 may be adjusted lengthwise along the rocker arms for a purpose to be hereinafter explained. When the bolts are tightened, the plates 13 will be securely clamped in their adjusted positions. Each plate 13 is provided with an upstanding ear 16 to serve as an element of a hinge connecting it with a platform which will now be explained.

The platform comprises side bars 17 which are connected by end bars 18, the end bars 18 being connected by longitudinally extending slats 19 which form the upper surface of the platform. Bars 20 are secured by connecting strips 21 and 22, to the side bars 17 of the platform in an inclined relation thereto, so that the bars 20 form with the platform a rigid auxiliary frame. The bars 20 are hinged at 23 to the ears 16 of the plates 13 so that the platform will be hingedly or articulately connected through plates 13 to the rocker arms 11. A cross beam 24 extends between the side bars 20 of the auxiliary frame of the platform, and is provided with a downwardly extending plate 25 which terminates at a level slightly above the upper surface of the slats 19 and may be referred to as a guide.

The rocker arms 11 are connected to one another by a cross plate 26 which terminates in a shoulder 27 along its forward or front edge at approximately the hinge pin 12,

The bar 25 extends beneath the overhanging section of the sill 4, so that when the rocker arms 11 are swung downwardly, from the position shown in Fig. 1 to the position shown in Fig. 2 (which positions are also shown in full and dotted lines, respectively, in Fig. 3), the shoulder edge 27 will move about the pin 12 and allow the sill 4 to swing downwardly to a slight extent, as shown also 10 in dotted lines in Fig. 3.

A pair of cables 28 are attached to the rear ends of the side bars 17 of the platform, and extend upwardly over pulleys 29 carried by the upper frame members 2 and 15 thence downwardly to the forward end of the frame where they are wound around the drum of a windlass 30. A hand wheel 31 is connected to the windlass for operating the same to wind up or release the cables 20 28. Suitable means, not shown, may be provided for securing the hand wheel 31 in various adjusted angular positions.

Additional cables 32 are also secured to the side bars 17 of the platform and extend 25 upwardly over pulleys 33 carried by the rear ends of the clamping levers 9 and thence forwardly and around the drum of a windlass 34 which is rotatably supported between the forward end corner posts 1 of the 30 frame. A hand wheel 35 is secured to the windlass for enabling its manual operation in either direction, and suitable securing means, not shown, may be provided for holding it in different adjusted angular positions. Other cables 36 are attached to the 35 rear end of the clamping levers 9, extend upwardly and over pulleys 37 carried by the said frame members 2, and then downwardly, carrying at their lower ends suitable counterweights 38.

Cables 39 are secured to the free ends of the rocker arms 11 and extend downwardly, endwise, and forwardly, passing beneath rollers 40 provided at the forward ends of the runners 3, and thence to a suitable operating device (not shown). Other cables 41 are also attached to the free ends of the rocker arms 11, pass upwardly over pulleys 42 carried by the side members of the frame, thence downwardly around pulleys 43 carried by the runners 3, and thence forwardly and endwise of the frame to suitable operating devices. The ground beneath the frame or machine may be excavated as at 44, so as 50 to provide a clearance for the rocker arms 11 when they are swung downwardly for a purpose to be explained presently.

In the operation of the machine, the strip of material 45, which is to be bent, is passed 60 over the platform endwise thereof, beneath the plate or nose 25 of the cross beam 24, and then over the sill 4 beneath the clamping gate 6. When the forward end of the strip 45 is at the desired distance from the overhanging edge of the sill 4, the hand

wheel 35 is operated to wind up the cables 32, which in shortening will pull the clamping lever 9 toward the platform. During this movement, the clamping levers will depress the clamping gate into clamping engagement with the sill 4 and effectively secure the strip 45 against displacement relatively thereto. The operating device which is connected to the cables 39 is then operated so as to draw up the cables 39, the cables 41 70 being free, and this operation causes a downward and forward movement of the rocker arms 11.

The rocker arms in moving downwardly will carry downwardly the forward end of the platform, and during this movement operators at the hand wheels 31 and 35 will operate the wheels to release the cables 28 and 32 slightly and allow the rear end of the platform to lower in accordance with the downward movement of the forward end of the platform. The platform will, therefore, move through approximately parallel positions as the rocker arms move downwardly and forwardly. The nose of the cross plate 25, which acts as a guide for confining the strip 45 against the face of the platform, will depress the strip and bend it over the rear edge of the sill 4, and the platform will bend the strip about the nose of the cross plate 25 so that when the platform and rocker arms have moved into a step-like relation with the sill 4, such as shown in Fig. 2, the strip 45 will have been given a double bend with a resulting step-like form. 100

During the downward movement of the rocker arms 11, the downward movement of the shoulder or edge 27 of the cross plate 28, as shown in Fig. 3, will permit a slight downward swinging movement of the sill 4 upon the side of its pivot adjacent the platform. The platform in moving downwardly will act through the cables 32 to depress further the clamping levers 9 and force the clamping gate 6 to follow the sill 4 in its downwardly swinging movement without releasing the strip 45. 125

In order to bend the strip into right angles, the machine must first bend it slightly beyond the desired extent, as the strip will spring back slightly when released. Unless the edge of the sill, over which the strip is bent is lowered slightly, the machine could not bend the strip beyond right angles because the travel of the nose 25 of the platform is not concentric about the edge of the sill over which the strip is bent, and therefore movement of the nose 25 beyond the lower 90° position would cause a stretching of the strip between bends unless the edge of the sill is lowered proportionately. By lowering the bending edge of the sill in this manner it is possible to bend the strips into Z shapes as well as to place right-angular bends therein, and to bend the strip far 130

enough to compensate for the return spring action of the strip when released after being bent.

After this bending operation has been completed, the operator will release the hand wheel 35, and the slack provided in the cables 32 will enable the counterweight 38 to elevate the clamping levers 9 and thus release the clamping gate. The lower section 6^a 10 of the clamping gate may then be swung laterally and upwardly, such as to the rear into the position shown in dotted lines in Fig. 1, which releases the strip 45. The cables 41 may be drawn to return the rocker 15 arms 11 and the platform to their approximately horizontal positions, during which movement the strip 45 with the bend therein will be carried upwardly. During the return of the rocker arms, the cables 39 will, 20 of course, be released, and the hand wheel 31 will be operated to elevate the rear end of the platform in accordance with the elevation of the forward end.

The strips 45 may then be shifted forwardly until the point where a new bend is to be made, is over the sill 4, this forward movement being permitted through the space available when the lower section of the clamping gate is swung upwardly. After 25 the strip has again been positioned over the sill 4, the lower section of the clamping gate may be swung downwardly into alignment with the upper section, and the bending operation repeated as before explained.

With this device it will be obvious that the strip 45 may be passed forwardly through the machine, and the bends placed therein in a simple, accurate, and rapid manner. In the bending of the reinforcement 30 for concrete steps and the like, the reinforcement commonly used is in the nature of a wire fabric, similar to fencing, but it will be obvious that strips of other material may have bends placed therein in a similar 35 manner within the principle and scope of this invention. It will be obvious that various changes in the details and arrangement of parts, herein described and illustrated for the purpose of explaining the nature of the invention, may be made by those skilled 40 in the art within the principle and scope of the invention as expressed in the appended claims.

Claims:

1. In a bending machine, a pair of clamping elements between which the strip to be bent is fed and at intervals clamped therebetween, a pivoted rocker member along which the strip passes, a guide for said strip 45 hingedly connected to said rocker member at a distance from the pivot of the latter, and means for operating said rocker member to carry the guide to one side of the plane of the clamped portion of the strip, whereby a bend will be placed in the strip.

2. In a bending machine, a pair of clamping elements between which the strip to be bent is fed and at intervals clamped therebetween, a bending shoulder over which the strip passes at one side of the clamping elements, a guide through which the strip passes at a distance from said shoulder, and means for swinging said guide to a position at one side of the plane of the strip between the shoulder and the clamping elements, whereby a bend will be created in said strip. 70

3. In a bending machine, a plurality of members mounted to lie normally in substantially the same plane and relatively movable into a step-like relative position, means for clamping to one of said members the strip to be bent, and a guide element against which the strip passes carried by the other member and confining the strip to said member, whereby when the strip is clamped to said one of the members and the members are moved into a relative step-like position, the strip will have a bend placed therein corresponding to the character of the step-like relation of the members. 80

4. In a bending machine, a frame, a sill on said frame over which a strip is to be bent, a clamping device for clamping the strip against movement relatively to said sill, a platform for supporting the strip normally in substantially the plane of the sill and having a guide at the end thereof adjacent to but spaced from the sill, through which guide the strip passes, and means for causing a relative movement between said platform and sill into a step-like relation to one another, whereby the strip will be given a step-like configuration. 90

5. The machine substantially as set forth in claim 4 in which the guide is adjustable toward and from the sill in order to vary the distance between the bends of each step placed in the strip. 95

6. In a bending machine, a frame, a sill on said frame over which a strip is to be bent, a clamping device for clamping the strip against movement relatively to said sill, a pivoted rocker member movable about its pivot into a position at an angle thereto, a platform against which the strip passes articulately connected to said member, said platform when the rocker member is parallel with the plane of said sill forming a substantial continuation of the sill, and having at the connected end a guide for confining the strip against the platform, means for rocking the member into a position at an angle to the sill, and means for supporting the platform, and permitting bodily movement with the member into a position at a desired angle thereto. 110

7. The machine substantially as set forth in claim 6 in which the connection between the platform and member is adjustable along 125

- the member whereby the distance between bends may be varied.
8. In a bending machine, a frame, a sill on the frame over which a strip is to bent, a clamping device for securing the strip against movement relatively to said sill, a pair of rocker arms pivoted to the frame below the sill for movement about an axis parallel with the sill, plates secured to said arms and adjustable lengthwise thereof, a platform hinged between the plates and supported so as to form a substantial continuation of the sill when the arms are approximately parallel to the sill, said platform having at its hinged end a bar extending thereover crosswise in spaced relation to the surface thereof for confining the strip to the platform, means for rocking the arms into a position at an angle to the sill.
- 20 9. In a bending machine, a plurality of members mounted to lie normally in substantially the same plane and relatively movable into a step-like relative position, means for securing a strip to be bent against movement relatively to one of said members, a guide carried by the other of said members for confining the strip thereagainst, and means for producing relative movement between the members into a step-like relation with respect to one another, whereby the strip will be bent into a corresponding step-like form.
10. In a bending machine, a pair of clamping elements between which the strip to be bent is fed and at intervals clamped therebetween, a bending shoulder over which the strip passes at one side of the clamping elements, a guide through which the strip passes at a distance from said shoulder, and means for swinging said guide to a position at one side of the plane of the strip between the shoulder and the clamping elements, whereby a bend will be created in said strip, said shoulder being movable slightly toward the guide during the bending operation to permit of the movement of the guide in excess of 90° from its starting position and thus bend the strip into a Z-shape.
11. In a bending machine, a plurality of members mounted to lie normally in substantially the same plane and relatively movable into a step-like relative position, means for clamping to one of said members the strip to be bent, and a guide against which the strip passes carried by the other member for confining the strip thereto, whereby when the strip is clamped to said one of the members and the members are moved into a relative step-like position, the strip will have a bend placed therein corresponding to the character of the step-like relation of the members, said members having a slight approaching movement at the bending shoulders during movement into a step-like relation whereby the step-like relation may be Z-shaped.
12. In a bending machine, a frame, a sill pivotally mounted in said frame and having a shoulder at one side of and parallel to its pivoted axis over which a strip is to be bent, means for clamping the strip against movement relatively to said sill, a guide device for said strip movable angularly about the bending shoulder of the sill to place a Z-shaped bend in the strip, and means normally holding the sill against tilting toward the axis of angular movement of the guide device and permitting some tilting of the sill during the bending operation as the Z-shape becomes more pronounced, whereby the bending shoulder may approach the guide device and allow angular movement of the guide device in excess of 90° from its initial position where it lies substantially in the plane of the sill.

In witness whereof, I hereunto subscribe my signature.

CLARENCE S. CRANE.
